DE-582

EX

OR D 16,500

DESIGN FOR A RUG.

Design No. 16,500, dated February 2, 1886.

UNITED STATES PATENT OFFICE.

ADOLPH PETZOLD, OF PHILADELPHIA, PENNSYLVANIA, ASSIGNOR TO
JOHN BROMLEY & SONS, OF SAME PLACE.

DESIGN FOR A RUG.

SPECIFICATION forming part of Design No. 16,500, dated February 2, 1886.

Application filed November 18, 1885. Serial No. 181,255. Term of patent 34 years.

To all whom it may concern:

Be it known that I, ADOLPH PETZOLD, a citizen of the United States, residing at Philadelphia, in the county of Philadelphia and State of Pennsylvania, have invented and produced a new and original Design for a Rug; and I do hereby declare that the photographic print accompanying this specification conveys to any one skilled in the art a clear understanding of the same, and is sufficient to enable such persons to use my invention.

The leading feature of my design consists in a triple panel-center ornamented by conventional floral figures, as shown in the photographic print. These panels are divided and surrounded by a plain narrow border, A. This narrow border A is surrounded by a wide border, B, ornamented by the representation of a series of twigs or small branches consisting of five leaves. Between each twig is shown the representation of a flower. The

outer surrounding border, C, is formed of a series of squares, the whole as shown in the photographic print accompanying this specification.

The photographic print illustrates and represents one half of the design or rug. The other half, described but not shown, is exactly like it.

What I claim as my invention is—

The design for a rug, consisting of a triple panel-center ornamented by floral figures, as shown, a plain narrow border, A, a wide border, B, ornamented by a series of twigs, leaves, and flowers, as shown and described, and an outer narrow border, C, composed of a series of squares, the whole as shown and described.

ADOLPH PETZOLD.

Witnesses:

JOHN SHINN,

J. GORDON SHOWAKER.
